UNITED STATES PATENT OFFICE

GEORGE W. SWIFT, JR., OF BORDENTOWN, NEW JERSEY, ASSIGNOR TO GEORGE W. SWIFT, JR., INC., OF BORDENTOWN, NEW JERSEY, A CORPORATION OF NEW JERSEY

EGG CASE FILLER

Application filed October 27, 1930. Serial No. 491,447.

This invention relates to egg case fillers in which a plurality of egg-holding pockets are integrally formed in a single sheet of material. The primary object of my invention 5 is to provide an improved construction for an article of this nature whereby the packing of eggs in an egg case may be facilitated to economize the time and effort of the packers and whereby the eggs may be better 10 packed and protected against damage. Toward the attainment of this purpose, my invention contemplates an integrally-formed egg case filler with pockets of sufficient depth to completely receive the eggs and with the 15 adjacently-disposed walls of different groups of pockets forming together suitable columns or supports for a filler flat which constitutes a cover for the pockets of a lower egg case filler and a support for another egg case 20 filler arranged thereabove. One of the objects of my invention is to improve the form of the pocket-forming walls of an egg case filler of this nature by virtue of which the 25 pockets may be made of sufficient depth to completely house the eggs while at the same time facilitating the removal of eggs therefrom one at a time. More specifically stated, my invention contemplates an integrally-constructed egg case filler comprising top flat- 30 wall portions or insular platforms spaced from each other in a common plane and intermediately arranged egg-receiving pockets depending therefrom, adjacent pockets of said filler being provided with intercommunicating grooves or recesses extending downwardly from the common plane of said insular platforms for permitting access to eggs contained in said pockets, the walls of said 35 pockets being provided with alternately-arranged inset and outset portions, said inset portions converging downwardly from said insular platforms and forming therewith supporting columns for a super-imposed filler 40 flat or cushion-flat which in effect forms a closure for all of said pockets, said outset portions extending from the bottoms of said pockets to said grooves or recesses. Another 45 object of my invention is to provide an improved cushion or bumper construction 50

around the perimetral edges of the egg case filler.

Other and more particular objects of my invention will appear in the specification, the structural features appertaining thereto being recited in the appended claims. 55

In the drawings which illustrate my invention in a preferred embodiment,

Figure 1 is a top plan view of a portion of one of my improved egg case fillers; 60

Figure 2 is a fragmentary vertical section of a plurality of my improved egg case fillers nested one within the other;

Figure 3 is a vertical longitudinal section of one end of an egg case packed with my 65 improved egg case fillers.

Referring more particularly to the drawings, my improved egg case filler may be constructed of any suitable material such, for example, as paper pulp and by any preferred method of treatment whereby a structure of the character described below can be formed. The present application relates to the finished product which is integrally formed and comprises a plurality of insular platforms 70

which are separated from each other in all directions and a multiple series of egg-receiving pockets 2 which depend below the common plane of and are arranged intermediately with respect to said insular platforms. By an inspection of the drawings, it will be seen that each of the egg-receiving pockets 2 is provided with recesses 3 in its lateral wall on four sides, said recesses extending downwardly from said common 85 plane of the insular platforms. The recesses 3 on two sides of each of the corner pockets; on three sides of each of the side edge pockets not at the corners; and on all four sides of each of the remaining pockets are connected by transverse downwardly-arched trough-forming walls 4 which provide intercommunicating channels between said pockets below the common plane of said insular platforms of the filler. Said corner pockets on 90

two sides of each and said side pockets on one side of each are provided with recesses 5 with closed walls 6, the lateral walls of recesses 5 and the end walls 6 forming a series of cushions or bumpers of trough-like 95 100

cross-section around the side edges of the 5
filler. As shown best in Figures 1 and 3
of the drawings, the lateral wall of each egg-
receiving pocket 2 comprises relatively inset
portions 7 which are contracted downwardly
from the insular platforms 1 and relatively
outset portions 8 which are contracted down-
wardly from the downwardly-arched trough-
forming walls 4. Said inset and outset por-
10
tions of the pocket walls are united along
their lateral edges to form closed rounded
walls which are preferably provided with
flattened surfaces 9 at the bottom to secure
a firm seating of the fillers upon flat boards
15
10 which are interposed between successive
fillers in packing an egg case. By an inspec-
tion of Figure 1, it will now be understood,
according to the present embodiment of my
invention, that each of the insular platforms
20
1 surmounts four of the inset portions 7 of
four different pockets to form in effect a sup-
porting column for the flat board 10 or filler-
flat which rests thereon and constitutes a
cover for all of the egg-containing pockets.
25
As may be understood from Figure 3, each
pocket is enlarged upwardly and is integrally
formed throughout its full depth so that an
egg placed on end in said pocket is positively
confined in a separate chamber as soon as
30
the flat board 10 or filler-flat is placed over
its opening at the top of the pocket. More-
over, the egg is cushioned by the inset por-
tions 7 of the pocket and is exposed to free
ventilation through the trough-like passages
35
formed by the downwardly-arched walls to
provide intercommunication between the
pockets, the relatively outset portions 8 of
the pockets permitting access of air to the
bottom of the pocket.
40
In packing eggs with my improved filler,
I preferably employ an egg case comprising
end walls 11 (only one being shown in Fig-
ure 3) connected by laterally-spaced strips
12 at top and bottom which provide longi-
45
tudinal slots and thus freely admit the out-
side air to the egg case. Egg case cushion-
flats of any suitable construction may be in-
terposed between the top and bottom walls
of the egg case and the top and bottom layers
50
of eggs therein. Preferably, however, I em-
ploy ventilated cushion-flats of the character
shown, described and claimed in my copend-
ing application, Serial No. 347,891, which
was filed in the U. S. Patent Office under
55
date of March 18, 1929. Thus, each of said
top and bottom cushion-flats comprises a flat
board or web 13 and a corrugated board or
web 14 attached thereto, the corrugations in
said corrugated web being of sufficient size
60
to give the desired cushioning effect for the
entire burden of the egg case. In this con-
nection, it will be understood that the bottom
pocket-forming filler rests squarely upon the
inwardly-presented flat board 13 of the bot-
65
tom cushion-flat and by means of the col-

umnar supports, provide a substantially rigid
foundation for the next higher filler through
the interposed board or flat 10. At the top,
the top cushion-flat serves as a closure for
the uppermost filler. When desired, the ven-
70
tilating effects in the egg case may be fur-
ther increased by providing suitable holes
or openings in the flat and corrugated webs
of the cushion-flats as well as in the filler-
flats 10 as shown and described in my above-
75
identified application.

I claim:

1. A filler tray for egg cases provided with
pockets open at the top, insular platforms
disposed in a common plane above the top
surfaces of eggs placed in said pockets, each
of said insular platforms being centrally ar-
ranged with respect to the top openings of
a group of said pockets, said pockets com-
prising substantially ovate lower half por-
tions disposed below the common axial plane
of said eggs and upwardly-flared upper half
portions extending above said common axial
plane of the eggs to the common plane of
said insular platforms, downwardly-arched
walls respectively depending from and be-
tween the edges of adjacent insular platforms
to a common plane adjacent said common ax-
ial plane of the eggs, said downwardly-arched
walls with their upwardly-divergent limbs
95
intersecting the upper half portions of adja-
cent pockets to form upwardly-widened chan-
nels disposed above the common axial planes
of eggs reposing in said pockets.

2. A filler tray for egg cases provided with
full length pockets arranged lengthwise on
vertical axes and open at the top, insular plat-
forms arranged in a common plane above the
top surfaces of eggs placed on end in said
pockets, each of said insular platforms be-
ing connected to the upper edges of a group
of pockets, the lateral wall of each of said
pockets comprising laterally-spaced relative-
ly inset portions extending the full depth of
said pocket and relatively outset bottom por-
tions intervening between the lower portions
of said full-depth portions, and downwardly-
arched walls extending downwardly from
and between the spaced edges of adjacent
insular platforms, said downwardly-arched
walls being joined to the side edges of said
relatively inset portions and to the upper
edges of said relatively outset bottom por-
tions for providing channels extending be-
tween the upper portions of adjacent pockets.
110

3. An egg case filler comprising a plurality
of filler trays constructed as recited in claim
2 and arranged one above the other, flat
boards interposed between successive tiers of
filler trays, each of said flat boards forming
a cover sheet for the open upper ends of the
pockets in an under filler tray and support-
ing webs for yieldably supporting the bottom
ends of the pockets of an upper filler tray
between groups of said insular platforms.
130

4. In an egg case, the combination with an outer case, of a plurality of filler trays constructed according to claim 1 and disposed one above another within said outer case, the 5 pockets of one filler tray being coaxially arranged with respect to the pockets of other filler trays disposed above and below said filler tray, filler flats interposed between the successive tiers of said filler trays for closing the open upper ends of a lower filler tray 10 and suspending an upper filler tray at points centrally disposed with respect to groups of insular platforms of said lower filler tray, and cushion flats respectively interposed between the top and bottom walls of said outer case and the uppermost and lowermost filler trays, said cushion flats comprising flat webs presented inwardly against the insular platforms of the uppermost filler tray and bottom ends of the pockets of the lowermost filler 15 tray and corrugated webs interposed between said flat webs and the top and bottom walls of said outer case.
